UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,152,040.

Specification of Letters Patent.

Patented Aug. 31, 1915.

Application filed April 11, 1914. Serial No. 831,286.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is, to provide a draft rigging of simple construction and efficient operation.

In the drawings forming part of this specification, Figure 1 is a side elevation of a draft rigging embodying my invention; Fig. 2 is a horizontal section taken on line 2—2 of Fig. 1; Fig. 3 is a cross section taken on line 3—3 of Fig. 1; Fig. 4 is a vertical longitudinal section showing the position of the parts when in full buff; Fig. 5 is a perspective view of the front follower; Fig. 6 is a perspective view of the rear follower.

Referring to the drawings, the numerals 7—7 indicate draft members or parts of the car frame to which the draft rigging is applied.

A stationary key 8 is mounted between the draft members, its ends being secured with perforations 9 in said draft members. In preferable construction, the opening 9 receives a collar 10 with which each reinforcing arm 11 for each draft member is provided, each of said arms having an opening 12 within which the ends of the key 8 are secured by suitable means, preferably the bolts 13—13. The said arms 11 are each forwardly extended, and each has a collar 14 entering an opening 15 with which each draft member is provided, the said collar surrounding an opening 16 in the said arm sufficiently longitudinally extended to permit the free forward and rearward movement of the ends of the coupler key 17 therein. The coupler key 17 engages the draw-bar 18 to the draft yoke 19, the same passing through a transverse slot 20 in the draw-bar and registering slots 21—21 in the adjacent limbs 22—22 of the draft yoke 19. The limbs 22 of the draft yoke 19 are also provided with transverse slots 23 through which

the key 8 passes, the said slots 23 being longitudinally extended to permit the free sliding movement of the yoke upon the key 8 in both forward and rearward movement of the draw-bar.

The front follower 24 comprises a block-like member 25 provided with spaced-apart, preferably integral rearwardly extended arms 26—26. The said follower is provided with spaced-apart longitudinally extended slots 27—27 extending along the inner faces of the arms 26 and so alined as to permit the passage of the limbs 22 of the yoke 19 therethrough. The said follower is also provided with transverse registering slots 30—30, which slots are formed through the forward portion of the block-like member 25, as indicated at the numeral 32 in Fig. 5 of the drawings, and through the arms 26—26 of the said follower, the surrounding wall of said slots in the arms of the follower being reinforced in preferable construction by the preferably integral outwardly extending shoulder 31. The key 8 passes through said slots in the front follower, the slots engaging at their rearward ends against the rear edge of the key 8 in normal position of the parts of the draft rigging, and being forwardly extended to permit the rearward movement of the front follower upon the said key 8 on rearward movement of the draw-bar.

The rear follower 33 comprises a block-like member 34 having forwardly extended arms 35—35, suitably spaced apart to permit the passage of said arms between the arms of the front follower; the said rear follower being provided with transversely extending slots 36—36 passing through the arms 35, the wall surrounding said slots being reinforced in preferable construction by the preferably integral shoulders 37—37.

The followers are each provided on their inner faces with upper and lower spring seats 38, each seat being provided with a boss 39 to assist in holding in position the compression resisting members hereinafter described. The compression resisting member comprise preferably an upper set of springs 40 and a lower set of springs 41. Each set of springs preferably consists of an outer coil 42 and an inner coil 43 nested therein. The upper set of springs 40 is seated between the upper spring seats of the

front and rear followers, and the lower set of springs is seated between the lower spring seats of the front and rear followers. In preferable construction, a bolt 44 passes through each set of springs, each of said bolts being secured at its ends in the front and rear followers, respectively, and preferably passing through the alined bosses 39. The key 8 passes through the perforations 36 in the rear follower, the said perforations registering with the perforations 30 in the front follower, and the arms of the front and rear followers overlapping, as is clearly shown in Figs. 1 and 2 of the drawings. In normal position of the rear follower the front ends of the slots 36 engage against the front edge of the key 8, the said slots 36 being sufficiently rearwardly extended to permit the forward movement 20 of the rear follower upon the key 8. The limbs of the yoke which pass through the longitudinal slots 27 in the front follower, pass along the inner faces of the arms 26 of the front follower and along the outer faces 25 of the arms 35 of the rear follower, the rear connecting member 47 of the draft yoke engaging against the rear face 48 of the rear follower in normal position of the parts of the draft rigging.

30 On forward movement of the draw-bar, the draft yoke 19 is drawn forwardly by the coupler key 17, the said yoke sliding upon the key 8 and drawing the rear follower forwardly, the said follower being 35 supported by, and sliding upon the key 8, and compressing the springs against the front follower, which is held against forward movement through the engagement of the key 8 against the rear end of the slot 30 40 in the arms thereof.

On rearward movement of the draw-bar, the draw-bar forces the front follower rearwardly, the same sliding upon the key 8 and compressing the springs against the rear follower, the rear follower being held against rearward movement by the key 8 engaging against the forward ends of the slots 36 in the rear follower's arms. The arms or extensions of the followers are preferably of 45 lesser vertical width than the block-like portions of the followers, and the key 8 is preferably flat and wide to afford resistance to the heavy shocks to which the same is subjected. The key 8 serves as stop member for 50 both of the followers, and is a supporting member for the followers, yoke, and the compression resisting members mounted between the followers.

55 I claim:—

60 1. In a draft gear for railway cars, a pair of relatively movable followers, compression-resisting elements between the followers, and a pin or key passing through and between the followers to limit their approaching and their separating movements.

2. In a draft gear for railway cars, relatively movable members, compression-resisting elements between said members, and a key, each of the movable members having slotted extensions slidably engaging said key, said extensions projecting from opposed faces of said members. 70

3. In a draft gear for railway cars, relatively movable members, compression-resisting elements between said members, and a key, each of the movable members having slotted extensions on the sides thereof, said extensions having a limited longitudinal movement upon the key. 75

4. In a draft gear for railway cars, relatively movable members, compression-resisting elements between said members, and a key, located between said elements, each of the movable members having integral slotted extensions slidably engaging the key. 80

5. In a draft gear for railway cars, relatively movable followers, compression-resisting elements between the followers, and a key, each of the followers having integral slotted extensions slidably engaging the key, 90 said extensions overlapping each other and projecting from opposed faces of said members.

6. In a draft rigging for railway cars, the combination with the draft members of longitudinally movable followers, compression-resisting elements between the followers, a stationary key extending between the draft members and intermediate the followers, the followers slidably engaging the key. 95

7. In a draft rigging for railway cars, the combination with the draft members, of longitudinally movable followers, compression-resisting elements between the followers, a stationary key extending between the draft members and intermediate the followers, the followers being provided with extensions slidably engaging the key. 100

8. In a draft rigging for railway cars, the combination with draft members of longitudinally movable followers, compression-resisting elements between the followers, and a stationary key extending between the draft members and intermediate the followers, the followers each having integral slotted extensions slidably engaging the key. 110

9. In a draft rigging for railway cars, the combination with draft members, followers, draw-bar, yoke and springs between the followers, of means for limiting the movement of the followers, comprising slotted extensions upon the followers, and a key stationary in the draft members and between the followers, the said extensions having sliding movement upon the key. 120

10. In a draft rigging for railway cars, in combination, draft members, a draw-bar, a yoke slidably connected to the draw-bar, longitudinally movable members within the yoke, compression-resisting members be- 130

tween the longitudinally movable members, and a key, the said key being stationary in the draft members and between the longitudinally movable members, the longitudinally movable members having a sliding engagement with the key.

11. In a draft rigging for railway cars, in combination, draft members, a draw-bar, a yoke secured thereto, longitudinally movable members within the yoke, compression-resisting members between the longitudinally movable members, and a key, the longitudinally movable members and the yoke being in sliding engagement with said key.

12. In a draft rigging for railway cars, in combination, draft members, a stationary key extending between the same, followers slidably mounted on the key, compression-resisting members between the followers, a draw-bar, and means extending through one follower and around the other for operatively connecting the draw-bar to the followers.

13. In a draft rigging for railway cars, in combination, draft members, a stationary key extending between the same, followers slidably mounted on the key, compression-resisting members between the followers, a draw-bar, and means extending through one follower and around the other for operatively connecting the draw-bar to the followers, the key stopping the rearward movement of the rear follower on rearward movement of the draw-bar, and stopping the forward movement of the front follower on forward movement of the draw-bar.

14. In a draft rigging for railway cars, in combination, draft members, a draw-bar, a yoke connected thereto, front and rear followers, compression-resisting members between the followers, and a key, the followers having overlapping slotted extensions, the key being mounted between the draft members and passing through the slots in the followers' extensions.

15. In a draft rigging for railway cars, in combination, draft members, a stationary key between the same, a draw-bar, a yoke connected thereto, longitudinally movable members within the yoke, compression-resisting means mounted between said members, the yoke and longitudinally movable members slidably operating upon the stationary key and being supported thereby, the key passing between the longitudinally movable members within the yoke.

16. In a draft rigging for railway cars, the combination with the draft members, of a stationary key extending between the same, followers and compression-resisting members between the followers, the stationary key passing between the followers, and each follower having a limited forward and rearward movement upon the key.

17. In a draft rigging for railway cars, the combination with the draft members, of

a stationary key extending between the same, followers arranged on opposite sides of the key, and compression-resisting members between the followers, the rear follower having a limited rearward movement upon the key, and the front follower having a limited forward movement upon the key.

18. In a draft rigging for railway cars, in combination, draft members, a draw-bar, a draft yoke slidably keyed to the draw-bar, followers, a stationary key extending between the draft members and passing between the followers, compression-resisting members between the followers, the followers being provided with extensions having longitudinal slots therein for the passage of a stationary key, and slidably operating on said key, the rear follower being stopped by said key on rearward movement of the draw-bar, and the front follower being stopped by said key on forward movement of the draw-bar.

19. In a draft rigging for railway cars, in combination, draft members, a draw-bar, a draft yoke connected thereto, followers, a stationary key mounted in the draft members and between the followers, compression-resisting members between the followers, the followers being provided with extensions having longitudinal slots therein for the passage of the stationary key, and slidably operating on said key, the rear follower being stopped by said key on rearward movement of the draw-bar, the front follower being stopped by said key on forward movement of the draw-bar, and the draft yoke slidably operating on the stationary key.

20. In a draft rigging for railway cars, in combination, draft members, a key stationary between said members, a slidable key passing through said members, followers slidably connected to the stationary key and oppositely arranged in reference to said key, a draw-bar connected to the slidable key, a draft yoke slidably connected to the slidable key and inclosing the followers, and compression-resisting members mounted between the followers.

21. In a draft rigging for railway cars, in combination, draft members, a draw-bar, a longitudinally movable yoke, followers, compression-resisting means between the followers, a stationary key and a slidable key between the draft members, the yoke having two pairs of slots, the slidable key passing through one pair of slots, and the stationary key passing through the other pair of slots, the followers being oppositely arranged in reference to the stationary key and having overlapping slotted extensions slidably engaging said key.

22. In a draft gear for railway cars, relatively movable members, compression-resisting elements between said members, and a key, the movable members being arranged on

- opposite sides of said key, and each having slotted overlapping extensions slidably engaging the key, said extensions projecting from opposed faces of said members.
- 5 23. In a draft rigging for railway ears, in combination, draft members, a key and a draft gear, the draft gear comprising followers oppositely arranged in reference to the key, and compression-resisting elements 10 mounted between the followers, the said followers slidably engaging the key, the key being stationary between the draft members and located intermediate said followers to support the draft gear and limit the separating movement of the followers.
- 15 24. In a draft rigging for railway cars, in combination, draft members, followers, springs and a single key, the key being stationary in the draft members, the followers 20 being spaced apart on either side of the key, and each having a slidable connection with the key, the springs being mounted between the followers both above and below the key.
- 25 25. In a draft gear having followers and springs between the followers, a means of stopping either follower while permitting movement of the other follower, comprising meeting arms extended from the followers, registering slots in the arms, and a key passing 30 between the followers, the key being of lesser width than the length of the slots passing through the followers' arms.
- 35 26. In a draft rigging for railway cars, in combination, draft members, a draw-bar, a draft yoke connected thereto, followers within the yoke, compression resisting members between the followers, and means for supporting and guiding the followers, comprising meeting longitudinally slotted arms 40 extended from the followers, and a flat key
- passing through the slots in said arm, the said key being secured to the draft members.
27. In a draft rigging for railway cars, in combination; draft members, key, a yoke and a draft gear, the draft gear comprising followers oppositely arranged in reference to the key, and compression resisting elements mounted between the followers, the said followers slidably engaging the key, the key being stationary between the draft members 45 to support the draft gear and limit the separating movement of the followers, the yoke passing around one follower and through the other follower.
28. In a draft rigging for railway cars, 50 in combination, draft members, followers and compression resisting members between the followers, a key stationary between the draft members, and a yoke, the followers being arranged on either side of the key, and having extensions slidably engaging the key, the yoke passing between the extensions on one follower, and straddling the extensions of the other follower.
29. In a draft rigging for railway cars, in combination, draft members, followers, compression resisting members between the followers, a key, and a yoke, the key being stationary in the draft members, the followers 55 being provided with slotted extensions slidably engaging the key, one of said followers being provided with longitudinal slots, the yoke passing around one follower and through the longitudinal slots in the other follower.

JOHN F. O'CONNOR.
